UNITED STATES PATENT OFFICE.

JOSEPH KRAMER, OF NEW YORK, N. Y., ASSIGNEE TO THE LOX SEAL CORPORATION, OF BROOKLYN, NEW YORK, A CORPORATION OF NEW YORK.

PILFERPROOF BOX.

Application filed March 26, 1925. Serial No. 18,558.

This invention relates to pilfer proof containers.

Pursuant to my invention, the parts of the box, carton or like container are provided with members coacting with the twine or like binding medium whereby the twine is precluded from displacement, and otherwise safeguards the contents of the container from pilfering.

Pursuant to the more preferred forms of my invention, the sides of the top or of the cover of the container are provided with openings for respectively receiving eye-members carried by the bottom part or by the tray of the container and at such spaced locations to project the respective eye portions of the eye-members through such openings. The twine or other binding medium is passed through the eyes and thus held in determined relation to the container and precludes slipping or otherwise displacing the twine in any attempt to pilfer the contents.

Each eye-member is preferably in the form of a clamp, preferably at its end opposite to its eye portion, such clamp affording ready positioning of the eye-member at its desired location on the bottom or tray part of the container.

The container may be of a two part type or telescoping cover and tray type. The tray part is preferably imperforate to prevent observation of the contents of the container, and also to preserve the strength and rigidity of such container part and to preclude the entry of any instrument or a finger therethrough. The tray of my preferred form of container is preferably of a blank having the side, end and corner portions of the blank creased to form the sides, ends and corners of the resulting tray by folding. The tray blank also preferably embodies an overlapping fold at its two sides to reinforce the stiffness of the tray along its direction of length and also coact to lock the corners in set-up position.

The cover part of my preferred form of container is formed of a blank having wholly creased parts excepting the openings for the eyes of the eye-clamp members, as aforesaid, the sides, ends and corners of the cover are formed by appropriate creases applied to the cover blank and by folding. The cover part is also preferably provided with an overlapping fold at its ends, thereby reinforcing the rigidity and stiffness of the cover in the direction of its ends, thus co-operating with the

reinforcements of the tray in the transverse direction.

Further features and objects of the invention will be more fully understood from the following detail description and the accompanying drawings, in which

Fig. 1 is a perspective view of a two-part or telescoping type of container embodying my invention;

Fig. 2 is an exploded view in perspective showing the cover of Fig. 1 removed from its tray, and also indicating one corner of the tray in partly assembled position;

Fig. 3 is a top plan view of a preferred form of the blank of the tray;

Fig. 4 is a top plan view of a preferred form of the cover;

Fig. 5 is a perspective view of a preferred form of an eye-clamp member for the tray or bottom part of the container;

Fig. 6 is a perspective view of a preferred form of coacting clip for the cover or top part of the container; and

Fig. 7 is a detail view in perspective showing a modification.

Referring to Figs. 1 and 2, the form of the particular container illustrated is of the two-part or telescoping cover and tray type. The cover is indicated at 10 and the tray at 11. The cover 10 is provided with the desired number of openings 12 for receiving the eye 13 of an eye-member 14. Such openings 12 are usually in the sides and ends of the cover 10. Each eye 13 is preferably disposed in substantially horizontal position when the eye-member 14 is in position on the tray 11. Each eye-member 14 is preferably of a clamp, as at its upper end 15, thus affording ready insertion of the clamp member 14 at the desired location on the tray 11.

Such arrangement affords the shipment of the eye-clamp members 14 separately from the container parts, which is a distinct advantage particularly with the type of tray and cover of my invention, providing for the complete knockdown of the tray and cover to wholly flat condition. The blank 16 of the tray 11 is shown in Fig. 3 and the blank 17 of the cover 10 is shown in Fig. 4; these parts are described more particularly hereinafter.

Such clamp portion 15 of the eye members is also advantageous for clamping and locking the overlapping folds 18, 19, see Figs. 2 and 3, of the sides of the tray 11, which folds 18, 19 coact to hold the corners of the tray 11.

in position. The folding in feature for the corners obviates the presence of any cut-in portion or opening otherwise necessary and obviates the use of staples and the like, thus preserving and in fact enhancing the stiffness and rigidity of the material of the tray as well as avoiding the presence of any opening through the tray permitting observation of the contents of the tray or for the entry of any tool or a finger in any attempt to pilfer.

Such overlapping folds 18, 19 provide for the increased stiffness of the sides 22, 23 of the tray 11, which in this instance is longitudinally of the tray 11.

Preferably, the cover is of the formation of the blank 17 shown in Fig. 4, including the overlapping folds 24, 25 extending longitudinally of the ends 26, 27 of the cover, thus securing re-inforcement of stiffness, rigidity and strength of the container as a whole in the direction transverse to the direction of the overlapping folds 18, 19 of the tray 11.

The preferred form of a tray for a two-part container embodying my invention is shown in Fig. 3. As indicated above, the opposite end portions 20, 21, and the opposite side portions 22, 23, together with the corners 27 are formed without any cutting-in or slots or openings of the blank 16 within the outer contour or margin of these parts. By the provision of the rectangular outline of creases 28, the opposite ends 20, 21 and the opposite sides 22, 23 are set up by folding along such creased lines 28. Each corner 27 is formed by the provision of a diagonal crease 29 and the right angular creases 30, 31. Like reference numbers indicate like parts for the respective corners 27.

The fold 18 for the side 22 and the fold 19 for the side 23, of the tray blank 16 is provided by the creased lines 32, 33.

As is indicated in the lower portion of Fig. 2, each corner 27 is formed by folding inwardly each corner portion 27 of the blank upon its diagonal creased line 29 and upon the right angular creases 30, 31, and after the corner has been fully folded, the overlap 18 is folded inwardly of the side 22 of the tray 11. The provision of the clamp portion 15 of the clamp member 14 upon being clipped over the overlapping fold 18, serves to hold the overlapping fold 18 in position and therewith each corner 27 is retained by the overlapping fold 18. A similar coaction and relation of parts obtains for the remaining two corners 27 by the provision of the overlapping fold 19 and the one or more clamp members 14. Preferably, two clamp members 14 are provided for each of the sides 22, 23.

Each clamp member 14 preferably has the re-entering loop 34 serving to be brought on the inner face of the fold 18, thereby locking the clamp portion 15 in its position about the fold 18 and relative to the side 22. A similar action is obtained for the re-entrant portions

34 of the one or more clamped members 14 of the overlapping fold 19 of the side 23 of the tray.

As is indicated above, for the regulation sizes of telescoping type of container, six 70 openings 12 are provided for the cover, usually distributed in special relation to one another by punching two of the openings 12 in each of the sides 35, 36 of the blank 17 of the cover and one opening 12 in each of the ends 75 26, 27 of the cover.

The blank 17 for the cover 10 is creased similarly as the blank 16 for the tray 11, and like creased lines are indicated by like reference numbers. The overlapping fold 24 for the end 26 of the tray blank 17 is had by the provision of the creased line 37 and the overlapping fold 25 for the end 27 by the creased line 38.

Upon bending the blank 17 for the cover 11 along its indicated creased lines, the overlapping folds 24, 25 serve to hold the respective corners 39 of the cover in position. The retaining of the overlapping folds 24, 25 may be had by the use of a simple clip passed over each fold 24, 25.

Preferably, the clip for the cover 10 is in the form indicated in Fig. 6, and comprising the bent body portion 40 of simple clip formation, and further comprising the re-entrant portion 41 serving to be brought about or hooked under the under edge of the respective overlapping folds 24, 25, to jointly lock the clip and overlapping fold in position. Such clip may further comprise the loop end portion 42 of a diameter to be passed or sprung over the eye 13 of a clamp member 14 after the eye 13 has been passed through an opening 12, whereby the clips 14, 40 perse serve to lock the cover 10 to the tray 11. The coaction of the clips 14, 40 is advantageous in holding the cover 10 on the tray 11 after the article has been enclosed within the container and preparatory to threading the twine or other binding medium about the container.

The twine 43, see Fig. 1, is passed through the eyes 13 of the respective clamp members 14 in any desired or preferred order of encircling the combined cover 10 and tray 11. By the provision of six eye-clamp members 14, the usual order of tying the twine 43 of two loops transversely of the length of the container and one loop longitudinally of the container may be had. The ends 44, 45 are knotted, as indicated at 46, to one another or to one of the loops in addition. If desired, the ends 45, 46 may be sealed by any desired or approved form of sealing means 47.

In threading the twine 43 through the eyes 13, the twine may be turned about on itself or knotted, as preferred.

My invention also provides for the use of the twine 48 passing peripherally about the opposite sides 35, 36 and opposite ends 26, 27

of the cover 10 to serve as the binding medium; the twine 48 may be employed in conjunction with the twine 43.

It will be observed that pursuant to my invention, no portion of the twine is brought within the interior of the tray or cover or otherwise within the container.

In Fig. 7 I have shown a modification of my eye-clamp member, comprising the clamp portion proper 43 formed by bending the material of the clamp member upon itself, and further comprising the locking end portion or portions 44 passing through a slot or two spaced openings 45 in either end 20, 21 of the tray 11. In such construction, such slot or pair of openings 45 is had within the otherwise imperforate ends 20, 21 of the tray 11, but such openings are located closely adjacent the upper edge of such ends. Furthermore, such openings 45 are concealed when the cover 10 is telescoped over the tray 11, and thus do not afford illegal inspection and are not in a position for passing any instrument or a finger therethrough.

It will be understood that overlapping folds similar to the folds 18, 19 may be positioned along the ends 20, 21 of the tray 11 and the overlapping folds 24, 25 of the cover correspondingly located along the sides 35, 36 of the cover.

In the shipment of the box parts as above described, the covers 10 and trays 11 are in wholly flattened condition and may be stacked and tied or enclosed in suitable containers as desired. Such fully flattened condition of the container parts enables a large number of the container parts to be enclosed within a given space, thereby also increasing the shipment quantity of the empty containers in a given truck or freight car, and also the storage of the containers preparatory to being set-up.

The clamp and clip members for my container are conveniently shipped separately, thereby also minimizing shipment space and storage. The twine may be advantageously cut of fixed lengths, thus saving the usual wastage incident to the cutting of twine in the operation of wrapping the individual containers.

The operations required in the assembly of the parts of my container are substantially no greater than that of setting-up the usual type of containers.

In a similar manner, my eye-member is applicable to containers of the folding box type and also for solid boxes. My invention is also adapted for the three part type of box, comprising separate cover and bottom parts and the central side and end part.

By the use of the folded-in corners, it will be observed that stapling or equivalent is obviated. In the usual stapled form of box, while permitting collapsibility, such collapsibility is had at the expense of weakening the

material at the folds, and when collapsed are of trebled thickness at spaced locations, thereby correspondingly decreasing the number of collapsed container parts in any given space of transportation or storage.

The parts of the telescope type or other two part container, and of the one part and three part types of containers are made of the usual material. The eye-members and eye clamp members and other forms of clips referred to hereinabove are preferably made of metal or the like either of round or flat stock and shaped pursuant to my invention.

Whereas, I have described my invention by reference to specific forms thereof, it will be understood that many changes and modifications may be made without departing from the spirit of the invention.

I claim:

1. The combination of a container including a tray, said tray being provided with an overlapping portion, the cover of the container being provided with a plurality of openings, a plurality of eye members corresponding in number and location to said openings and carried by said tray to project the eye portions through said openings, certain of said eye members engaging said overlapping portion to hold the same in position, a clip carried by said cover, said clip having a portion arranged to extend about the eye portion of one of said eye members when said cover is in position on said tray and a binding medium passing through said eye portions and exteriorly of said container.

2. The combination of a container including a tray, said tray being provided with an overlapping portion, the cover of the container being provided with a plurality of openings, a plurality of eye members corresponding in number and location to said openings and carried by said tray to project the eye portions through said openings, certain of said eye members engaging said overlapping portion to hold the same in position, said cover having an overlapping portion extending transversely to the overlapping portion of said tray, a clip engaging said overlapping portion, said clip having a portion arranged to extend about the eye portion of one of said eye members when said cover is in position on said tray and a binding medium passing through said eye portions and exteriorly of said container.

3. In a box construction, a box member formed by folding an integral blank along predetermined lines, whereby multi-ply portions are produced, said portions presenting an upper folded-over edge and a resilient clip element for retaining said member in set-up condition, said element comprising a wire shaped to provide a hook portion removably clampable at desired points over said folded-over edge to retain said plies in superposition, said hook portion being provided

at its end with a second hook portion for engagement about the free edge of one of said plies.

4. In a box construction, a set-up box member, a similarly constructed complementary closure member adapted to telescope the box member, and means for retaining the box member in set-up condition and also to lock said closure member thereto, said means comprising a clip element removably clampable over a desired point on the edge of the box member and having a head adapted to engage the closure member, said element comprising a wire medially looped to provide said head and having its ends shaped to form a hook portion.

5. In a box construction, a box member which includes overlapping portions, a closure member provided with a set of openings, a set of clip elements corresponding in number and location to said openings and carried by said box member, each clip element being provided with a head adapted to extend through one of said openings, and certain of said clip elements engaging about said overlapping portion to hold the same in position, and a second set of clips carried by the closure member, said last named clips having eyelets adapted to extend about the heads of certain of the first named clip elements when the closure is in position on said box member.

6. In a box construction, a box member formed by folding an integral flat blank along predetermined lines; whereby multi-ply por-

tions are produced, a complementary closure member similarly formed and adapted to telescope the box member, and means for retaining the box and closure members in set-up condition and also to lock them together, said means comprising a set of clip elements removably clampable over the edges of the box member portions to retain said plies in superposition, each of said elements having a head adapted to engage the closure member, and a second set of clips removably clampable over the edges of the closure member portions to retain the closure member plies in superposition, each of said last named clips having an eyelet adapted to engage over one of said heads.

7. For use with a set-up box member and a similarly constructed complementary closure member adapted to telescope the box member; a fastening device for retaining the box member in set-up condition and also to lock said closure member thereto, said device comprising a clip element having a portion constructed and arranged to be removably clampable over a desired point on the edge of the box member and having a head formed on said portion and adapted to pass through the closure member when the latter is applied to the set-up box member, said element comprising a wire medially looped to provide said head and having its ends shaped to provide a hook portion.

In testimony whereof I have signed this specification this 25th day of March, 1925.

JOSEPH KRAMER.
